THERMAL DIFFUSION APPARATUS AND METHOD

Arthur Letcher Jones, Lyndhurst, and Ernest C. Mitterberger, Maple Heights, Ohio, assignors to The Standard Oil Company, Cleveland, Ohio, a corporation of Ohio

Application March 27, 1952, Serial No. 278,848

4 Claims. (Cl. 210—52.5)

The present invention relates to a liquid thermal diffusion apparatus and method that is particularly suitable for separating small quantities of materials, such as may be desirable in assaying the applicability of thermal diffusion to a particular separation.

The separation, by thermal diffusion, of liquid mixture, a term intended herein to include mixtures and solutions liquid under operating conditions, into two dissimilar fractions is carried out in apparatus essentially comprising two liquid impervious walls, the opposed faces of which are smooth and spaced substantially equidistantly from one another to form a narrow slit, preferably having a width no greater than about 0.15", and means are provided to maintain the opposed walls at different temperatures to establish a temperature gradient across the slit, one of the walls being referred to as the "hot" wall and the other as the "cold" wall, the terms "hot" and "cold" being used in their relative rather than absolute sense. Apparatus and methods for carrying out liquid thermal diffusion on a continuous basis are described in U. S. Patents Nos. 2,541,069, 2,541,070 and 2,541,071.

It has been proposed heretofore to subject separable liquid mixtures to thermal diffusion in slits provided at the top and bottom ends with a reservoir, the volume of each reservoir being relatively large as compared with the volume of the slit. (Berichte, vol. 73, pages 249-269 (1940).) In operation, apparatus of this type would be filled with the liquid mixture and the opposed slit-forming wall faces would be maintained at different temperatures to create a temperature gradient across the slit. After many hours or several days, liquid would be removed separately from the two reservoirs and analysis would show them to be enriched in one or another of the components of the liquid mixture.

Apparatus of the type heretofore proposed is extremely inefficient from the point of view of degree of separation obtainable in relation to the time and heat energy consumed. It is for these reasons that earlier proposals to separate liquid mixtures by thermal diffusion remained nothing more than a laboratory curiosity for over eighty years.

The present invention is addressed particularly to static, as distinguished from continuous, liquid thermal diffusion apparatus that is extremely useful for separating small amounts of materials by thermal diffusion and to assay the potentialities of the process in separating components of any particular material. In some fields, such as medicine, where only small quantities need be separated, the apparatus and process may be used directly in the separating technique. The utility of the apparatus of this invention as a research tool, for example, is demonstrated by its ability to separate components of liquid mixtures that cannot, or can only with extreme difficulty, be separated by any other means, such as fractional distillation and extraction. Thus, for example, as will be described in more detail hereinafter, the apparatus of the present invention is capable of separating a mixture of cyclohexane, having a boiling point of 80.74° C. and 2,4-di-

2

methyl pentane, having a boiling point of 80.50° C. into fractions of high purity.

The apparatus of the present invention comprises two vertical, liquid impervious walls, the opposed faces of which are smooth and spaced substantially equidistantly from one another to form a narrow vertical slit, means for closing the slit at the top and bottom thereof to avoid reservoirs whereby all of the liquid to be treated is in the slit, means for relatively heating and cooling the walls to maintain a temperature gradient across the slit, and a plurality of ports communicating with the slit, one of the ports communicating with the slit at the lower end thereof and at least one other of the ports communicating with the slit at a preselected distance from the top of the slit. It is important that there be no reservoir in communication with the slit, the term "reservoir" being intended herein to refer to a space in which thermal diffusion does not take place by reason of either or both the absence of a temperature gradient or a width exceeding substantially the width of the slit.

The width of the slit formed by the opposed walls is extremely narrow, being no greater than 0.15". All other conditions being equal, the degree of separation increases with a reduction in slit width, and the time required to reach equilibrium increases with a reduction in slit width. Hence the choice of slit width for any specific separation is necessarily a compromise between the time available, the degree of separation desired and the facilities for constructing apparatus with the desired slit width. Inasmuch as the apparatus of the present invention is designed primarily for use where a high degree of separation is the main objective, the slit width is preferably below about 0.015".

The number of ports communicating with the slit is dependent upon the separation involved. Thus, for example, if indications are that the only component of a liquid mixture that is desired to be separated is the component which accumulates in the upper fifth of the slit, then it is necessary only to have two ports, one located one-fifth the distance from the top of the column for removing the desired separated component, and another at the bottom for draining the column after the desired component has been removed. On the other hand, where the desideratum is to find how many different fractions can be separated, or what portion of the slit contains the separated fraction, it is desirable to have a plurality of ports communicating with the slit at substantially equidistant levels.

The slit may be formed by any suitable means such as, for example, by concentric tubes in which the inner wall of the outer tube and the outer wall of the inner tube form an annular slit, or by flat, parallel plates. If desired, suitable means for spacing the opposed walls from one another, such as are disclosed in co-pending application Serial No. 271,182, filed February 12, 1952, may be utilized.

The method of the invention comprises forming a thin, vertical film of a preselected quantity of the liquid mixture to be subjected to thermal diffusion in a slit defined by smooth, liquid impervious, substantially equidistantly spaced wall surfaces, applying a temperature gradient across the film until the concentrations or compositions of dissimilar fractions at various levels of the film have reached substantial equilibrium conditions, and then removing separately the various dissimilar fractions.

The thickness of the vertical film should not be so great as to make negligible the degree of separation obtainable, nor so small as to increase unduly the time required to reach equilibrium conditions. It has been found that the thickness of the film should under no circumstances exceed about 0.15" and should preferably be no greater

than about 0.015". A lower limit of 0.005" is about as small as manufacturing tolerances will allow under ordinary conditions.

In one preferred embodiment of the method the liquid mixture to be subjected to thermal diffusion is introduced into a vertical slit through a port at the bottom thereof, the uppermost port or a vent being left open to allow air within the slit to be displaced by the liquid mixture. It is to be understood, of course, that the structure of the vent need not be the same as or similar to that of a port. When the column is filled, one of the slit-forming walls is relatively cooled and the other is relatively heated to produce a temperature gradient across the film of liquid within the slit. When the temperature of the column during operation reaches equilibrium, it is immaterial whether the charge port and the vent be left open or closed so long as there is no flow of liquid mixture through the charge port. The temperature gradient across the film is maintained until substantial separation, as distinguished from temperature, equilibrium conditions are obtained.

The port immediately below the vent is then opened to drain the uppermost portion of the slit, the next lower port is then opened to drain the next lower portion of the slit, and so on, until all portions of the slit have been separately drained.

The advantages and utility of the apparatus and method of this invention will become more apparent from the following detailed description made with reference to the accompanying drawing, wherein:

Figure 1 is a view in elevation of one embodiment of the apparatus; and

Figure 2 is a graphic representation of a separation obtained by subjecting a 50-50 mixture of 2,4-dimethyl pentane and cyclohexane to thermal diffusion in the apparatus illustrated in Figure 1.

Referring now to Figure 1, an annular slit 10 is formed by an inner tube 11 and an outer tube 12. The outer tube is successively wrapped with a protective covering 14, a resistance heating wire 16, and insulating tape 17. The inner and outer tubes 11 and 12 are suitably sealed together at the lower end 19 and at the upper end they are sealed by means of packing material 20 and a packing nut 21 that allows slight relative lengthwise movement between the tubes 11 and 12 upon being subjected to different temperatures. A plurality of ports 22 and a vent 23 communicating with the slit 10, are provided along the length of the outer tube 12. The ports 22 are provided with closures located as close to the slit as possible so that the volume of the material in the ports 22 is small. The ports 22 and the vent 23 may, for example, be of copper tubing or the like and the closures for a port may include a flange member 24 sweated or welded onto the port, a screw cap 25 and a gasket 26.

A 50-50 mixture by volume of 2,4-dimethyl pentane and cyclohexane was subjected to thermal diffusion in a column such as illustrated in Figure 1. The annular slit has an effective height of 5 feet, a width of 0.0115", and a volumetric capacity of 22.2 cc. Ten withdrawal ports 22 and a vent 23 are spaced six inches apart, beginning at the bottom of the column. The ports 22 and the vent 23 were each constructed of $\frac{1}{8}$ " copper tubing having an inside diameter of approximately 0.070" and a length of about $1\frac{1}{4}$ ". The outer tube 12 was maintained at a temperature of 105° F. by the heated resistance wire 16, and the inner tube 11 was maintained at a temperature of 64° F. by circulating tap water through it.

After 100 hours, ten fractions of 2.22 cc. each were separately and successively withdrawn by way of ports 22, the first fraction being withdrawn from the uppermost port 22, the second from the second highest port 22, and so on. The indices of refraction at 25° C. of the initial components and mixtures charged to the column and of the ten fractions separated are tabulated below

in Table I and are graphically illustrated in Figure 2 of the drawing:

Table I

Charge:	n_D^{25}
Cyclohexane (over 99% pure)	1.4240
2,4-dimethyl pentane (over 99% pure)	1.3794
Feed (50-50 mixture)	1.4018
Fraction (numbered from top):	
1	1.3792
2	1.3794
3	1.3798
4	1.3825
5	1.3890
6	1.4072
7	1.4148
8	1.4232
9	1.4234
10	1.4243

The data in the table indicate that the top 30% and bottom 30% are about equal in purity to the components, represented when purchased as being over 99% pure, used in blending the charge. This separation is believed to be remarkable because cyclohexane and 2,4-dimethyl pentane cannot be separated effectively by fractional distillation, their boiling points differing by only 0.24° C., or by chromatographic methods.

As an additional example, catalytically cracked residual oil boiling between 400 and 530° F. at 2 mm. was treated in the same apparatus. The hot wall was maintained at a temperature of 185° F. The cold wall was maintained at a temperature of 70 – 100° F. by circulating tap water entering at 70° F. and leaving at 100° F. The treating time was 164 hours.

The original material had a reddish-brown color and was a semi-solid at room temperatures. In contrast thereto, the top fraction was white and consisted almost entirely of high molecular weight normal paraffins, whereas the bottom fraction had a dark brown color and consisted almost entirely of high molecular weight polynuclear aromatics. The intermediate fractions represented gradations. For instance, the fourth fraction from the top was light yellow in color because it contained a noticeable amount of the bottom aromatic type fraction.

The physical data relating to the separation of catalytically cracked residual oil are tabulated below:

Table II

50	n_D^{25}	Ambient Temp. State	Color	Apparent Viscosity
Charge Fraction:	1.5700	Semi-Solid	Reddish-Brown	
1	1.54 $\pm$ 0.01	Solid	White	
2	1.451 $\pm$ 0.001	do	Light Yellow	
3	1.4570	Semi-Solid	Yellow	
4	1.4650	Liquid	Orange	
5	1.5000	do	Dark Orange	Low.
6	1.6001	do		Do.
7	1.6552	do		Medium.
8	1.6704	do		Do.
9	1.6821	do	Brown and progressively darker brown.	High.
10	1.6870	do		Do.
				Very high.

Infrared analysis of the fractions showed that the top fraction contained almost entirely high molecular weight normal paraffins and that the bottom fraction contained predominantly high molecular weight polynuclear aromatic compounds such as alkyl benzenethrenes and phenanthrenes, wherein the alkyl group was primarily methyl. These results were confirmed by an ultra-violet analysis over a 230–450 millimicron range.

From this example, the extent of the separation is readily apparent and it is possible to determine the size and operating conditions of a column on a commercial scale to effect any separation desired, i. e., a fraction limited to the top and bottom tenth, a fraction in which the top fifth and bottom fifth are combined, etc.

It will be readily apparent that the method and apparatus of this invention is applicable to the separation of many liquid mixtures that are difficult or incapable of separation by other methods.

It is also to be understood that modifications and changes to suit particular needs will at once become apparent to those skilled in the art upon reading this description. All such modifications and changes are intended to be included within the scope of this invention as defined in the accompanying claims.

We claim:

1. Static liquid thermal diffusion apparatus comprising two vertical, liquid-impervious walls, the opposed faces of which are smooth and spaced substantially equidistantly and not more than 0.15 inch apart to form a 15 narrow, vertical slit, means closing the slit at the ends thereof to confine liquid to be treated to the volume of the slit, means for relatively heating one wall and cooling the other wall to maintain a temperature gradient across the slit, an inlet communicating with said slit for introducing liquid to be treated into said slit, a vent communicating with the top of said slit, a plurality of short tubes of small inside diameter communicating with the slit at vertically spaced points along the length of said slit, and closures for sealing said tubes and said inlet, whereby liquid in the apparatus is confined substantially completely within the slit while subjected to thermal diffusion and a plurality of separate and distinct fractions thereof may be withdrawn from the slit by individual removal of the closures at spaced time intervals. 25

2. Static liquid thermal diffusion apparatus as defined in claim 1 wherein said tubes are equidistantly spaced along the length of the slit.

3. A method of separating a liquid mixture into a plurality of dissimilar fractions which comprises confining all of said mixture to be separated to a thin quiescent

vertical film not exceeding 0.015 inch thick, applying a temperature gradient across said film until the concentrations of dissimilar fractions at various levels thereof have reached substantial equilibrium conditions, and then removing separately the various dissimilar fractions at a plurality of levels spaced vertically along said film, said fractions being removed in succession from top to bottom of said film.

4. Static liquid thermal diffusion apparatus comprising two vertical, liquid-impervious walls, the opposed faces of which are smooth and spaced less than about 0.015" from one another to form a narrow, substantially uniform vertical slit, means closing the slit at the ends thereof to confine liquid to be treated to the volume of the slit, means for relatively heating one wall and cooling the other wall to maintain a temperature gradient across the slit, an inlet for filling said slit with liquid, a vent communicating with the top of said slit and a plurality of short tubes of small inside diameter communicating with the slit, one of said tubes communicating with the slit near the lower end thereof and at least one of said tubes communicating with the slit at a preselected distance from the top of the slit.
